CURTAIN TRIMMING

Hugo A. Klahre, Teaneck, N. J., assignor to Consolidated Trimming Corporation, New York, N. Y., a corporation of New York

Application July 8, 1938, Serial No. 218,065

5 Claims. (Cl. 2—278)

This invention relates to textile trimming material.

More particularly stated, the invention relates to trimming material especially designed and adapted for trimming the edges of curtains, although it should be understood that the material is not limited to such use.

The invention has for its object to provide an attractive trimming of the character described, so designed that it can be economically and expeditiously manufactured.

Further objects of the invention will appear from the following specification taken in connection with the drawing which forms a part of this application, and in which—

Fig. 1 is a plan view of a portion of the material, some of the elements being shown in exploded position;

Fig. 2 is a plan view of a portion of the finished material;

Fig. 3 is a side elevation of the material; and

Fig. 4 is a front elevation of the material.

In the form of the invention illustrated in the drawing, the main body of the material is formed by a plurality of oppositely extending loops A and B. These loops may be made in any desired manner, but as illustrated they are formed by bending or folding parallel strands of yarn 10 and 11 into zigzag form. A single strand of yarn or as many strands as desired may be combined to form the loops.

From the illustration in Figs. 1 and 2, it will be noted that the loops B at one edge of the material are disposed close together or substantially in abutting relation, whereas the loops A at the other edge of the material are disposed farther apart than the loops B, or in spaced relation.

After the zigzag folds or bends have been formed in the manner above described, the loops at the two edges of the fabric are secured in fixed relation with respect to each other in any suitable manner, as by stitching. Three rows of stitches, indicated at 12, 13 and 14, are shown at the upper edge of the fabric and in order to enhance the appearance of the edge, strands of yarn 15 are secured in position, as by knitting.

At the other edge of the fabric the loops A are held in spaced relation by a row 16 of stitches and this edge of the fabric is further ornamented by means of a looped strand of yarn 20 having oppositely extending loops C and D. The loops D are positioned intermediate the loops A of the body of the trimming material and assist in holding these loops in spaced relation, although it should be understood that the border of loops

is not necessary or essential to the invention, but that the loops A can be held in suitable spaced relation by the row of stitches 16.

In Fig. 2 there is also shown at the junction of the loops A and B, a strand 21 of yarn which may be secured in position in any desired manner, as by knitting.

From the above description and from the illustration in the drawing it will be evident that a given number of loops B at one edge of the material forms a shorter longitudinal length of material than the same number of loops A at the other edge of the material since the loops A are spaced farther apart than the loops B. This gives a very attractive ripple effect to the edge of the trimming material that is particularly advantageous when the material is used as a trimming for the vertical edges of curtains.

Although one specific embodiment of the invention has been particularly shown and described, it will be understood that the invention is capable of modification and that changes in the construction and in the arrangement of the various cooperating parts may be made without departing from the spirit or scope of the invention, as expressed in the following claims.

What I claim is:

1. Trimming material for the edges of fabrics, said trimming material consisting of a plurality of loops of yarn disposed side by side, successive loops extending in opposite directions, the loops at one edge of the trimming material being disposed side by side in close relation to each other, and the loops at the other edge being disposed side by side in spaced relation to each other so that the length formed by a given number of loops at one edge is greater than the length at the other edge formed by the same number of loops and means at one edge for securing the loops in contact with each other and means at the other edge for securing the loops in spaced relation at said latter edge.

2. Textile trimming material comprising a strip of material having intermediate the edges thereof a plurality of transverse lengths of yarn, disposed side by side, means at one of the edges of the material engaging and connecting together the ends of said lengths of yarn in contact with each other at said edge, the lengths being loose and unconnected between the edges of the material, diverging from one edge of the strip to the other edge thereof, and means at said latter edge engaging and retaining the lengths of yarn in spaced relation, said transverse lengths being

formed by bending a length of yarn back and forth in zigzag folds.

3. Textile trimming material comprising a strip of material having the body portion intermediate the edges of the strip formed of a plurality of oppositely extending loops of yarn disposed side by side, the loops at one edge being disposed closer together than the loops at the other edge of the strip, a looped border at the 10 edge of the strip having the loops disposed farther apart, the loops of the border being disposed between the loops at that edge of the strip to hold the loops at that edge in spaced relation, and means for securing the loops at the other 15 edge of the strip together.
4. Textile trimming material comprising a strip of material having intermediate the edges thereof a plurality of transverse lengths of yarn, disposed side by side, means at one of the edges of 20 the material engaging and holding together the ends of said lengths of yarn in contact with each

other, the lengths being loose and unconnected between the edges of the material, diverging from one edge of the strip to the other edge thereof, and means at the latter edge of the material engaging and retaining said lengths of yarn 5 in spaced relation at said edge.

5. Textile trimming material comprising a strip of material having intermediate the edges thereof a plurality of transverse lengths of yarn disposed side by side, the ends of the lengths 10 of yarn at one edge of the material being disposed in closer relationship to each other than the ends of the lengths of yarn at the other edge of the material, the lengths being loose and unconnected between the edges of the material, 15 diverging from one edge of the strip to the other edge thereof, and means adjacent each edge of the strip for maintaining the lengths of yarn in the relations set forth.

HUGO A. KLAHRE. 20
